UNITED STATES PATENT OFFICE.

WILLARD COWLES, OF WASHINGTON, DISTRICT OF COLUMBIA.

IMPROVEMENT IN APPARATUS FOR STEREOTYPING.

Specification forming part of Letters Patent No. 12,157, dated January 2, 1855.

To all whom it may concern:

Be it known that I, WILLARD COWLES, of the city of Washington, in the District of Columbia, have invented certain Improvements in Materials, Processes, and Apparatus made use of in the Art of Stereotyping; and I do hereby declare that the following is a full and exact description of the same, reference being had to the accompanying drawings and the letters marked thereon.

The nature of my invention consists in making molds from type or other matter by successive impressions with it upon the plastic material herein described, which is of sufficient toughness to admit of being easily molded without breaking, will harden in drying without cracking, and retain a perfect impression of the type, and which, when a plate of any material has been cast into or upon it, can be easily washed therefrom; also, in constructing furniture, frame, and bars, so as easily to determine the size, form, and bevel edges of the stereotype-plate, and, in combination with a metallic or other plate, its thickness; also, in dividing the plate in casting into two or more pieces by the use of metallic or other slips, as described, to give a better understanding of which I will proceed to give a more complete description.

I use a material for molds composed of fine tough clay, which has been well kneaded and intimately mixed with about one part of best treacle to twenty parts of clay, by weight. This mixture should remain from one to four days, when fermentation takes place and it attains its greatest toughness. When required for use, there is to be mixed with this mass plaster-of-paris enough to prevent cracking in drying. About three parts of dry plaster to five of the above mixture will ordinarily be sufficient, but the proportion required will vary with the quality of the plaster. The manner of making the mold is to spread this material in a thin coating upon a metallic or other plate, Figure 4, *ff* and pressing it several times successively upon the type or other matter to be molded, care being taken to moisten the type with pure spirits of turpentine or camphine previous to each impression to prevent the adhesion of the mold material thereto.

To determine the size, form, bevel edges, and thickness of the stereotype-plate, I use

furniture of a convenient and proper height and breadth, Figs. 1 and 5, *aa*, with its upper and lower surfaces perfectly parallel, with which to surround the type or other matter to be molded for the purpose of forming a bed, Fig. 4, *bb*, around the mold, upon which bed a metallic frame, Fig. 2, may be placed as hereinafter described, or within which bed may be retained the metallic or other bars, Fig. 3, as hereinafter described, which frame or bars are to determine the size, form, bevel edges, and, in combination with a metallic or other plate, the thickness of the stereotype-plate. I also use a casting-frame, Fig. 2, constructed of cast-iron or other material of sufficient strength, with its aperture exactly corresponding to the size and bevel edges of the required stereotype-plate, and its thickness such as, together with the difference between the height of the molding-furniture above described and that of the type shall be equal to the required thickness of the stereotype-plate; or I make use of bars, Fig. 3, of a length to suit the page, which laid, previous to the last impression, upon furniture as high as the type, less the required thickness of the stereotype-plate, become embedded in and adhere to the molds, and in place of the frame determine the size, form, and bevel of the stereotype-plates. The material used for the stereotype-plate being placed upon the mold and within the frame or bars, (which frame is first placed upon the bed of the mold, Fig. 4, *bb*, as represented at Fig. 6, *bb*) a metallic plate is laid upon it and the whole submitted to a pressure, which shall be sufficient to bring the plate in contact with the upper side of the frame, Fig. 2, or bars, Fig. 3. This frame may be made with shifting partitions, so as to be readily divided into compartments of any desired dimensions. The frame or bars should have openings upon the upper side, Figs. 2, 3, and 6, *cc*, to allow of the escape of superfluous material. The bars should also have longitudinal grooves, Fig. 3, *gg*, on the lower side, into which the mold material will be pressed and serve to keep the bars in their proper place during the operation of casting. It will be understood that the different materials and compositions made use of for constructing stereotype-plates require for the most part different degrees of heat and some, as cements, none at all. Dif-

ferent manipulation is also required, as for type-metal, fusible metal, cements, and materials composed of various substances the principal part of which is gutta-percha, india-rubber, or shellac.

When I wish to cast a page in several pieces, I place a lead, Fig. 5, *d d*, as high as the type, less the required thickness of the stereotype-plate, between the lines of the type wherever it is desired to have the stereotype-plate divided, thus forming a narrow groove. Metallic or other slips should be made of equal thickness with these leads and of a breadth which, together with that of the leads, shall correspond to the height of the type or other matter. Then before making the last impression in the formation of the mold these slips, Figs. 1 and 5, *e e*, are inserted in the grooves above mentioned, and after the impression they remain embedded in the mold, Figs. 4 and 6, *e e*. Upon making the cast these slips remain in it, dividing it where they occur to a sufficient depth to render it easily and accurately separable. These slips may also be used in the manner described when the mold is made in the ordinary way with plaster-of-paris or of any other material.

I do not claim the use of plaster-of-paris or clay for the making of molds for stereotyping; nor do I claim the making of molds by successive impressions; nor do I claim simply the use of furniture, nor the determination of the thickness of the stereotype-plate by means of bars or a frame placed upon the mold-plate; but

What I do claim as my invention, and desire to secure by Letters Patent, is—

1. The use of furniture of an exact and proper height for the purpose of forming a bed in and around the mold on which to place the metallic casting-frame, which gages the size, form, and bevel of the stereotype-plate, or which shall itself form a support on which bars are placed for the purpose of being pressed into the mold and embedded therein, thus taking the place of the frame.

2. The use of a frame placed upon a bed in and around the mold or in its place the use of bars pressed upon and into the mold, substantially for the purpose and in the manner described.

3. The use of slips of metal or other substance for the purpose of dividing the plate into two or more pieces, used substantially in the manner described or any similar manner of accomplishing the same object, whether these be used in combination or separately, or whether the material used in making the stereotype-plates be common type-metal or a compound in which a principal ingredient is gutta-percha, india-rubber, shellac, or any other substance or composition of which stereotype-plates are now or may hereafter be made.

WILLARD COWLES.
